UNITED STATES PATENT OFFICE.

ISAAC BEDICHIMER, OF PHILADELPHIA, PENNSYLVANIA.

DESIGN FOR A BADGE.

Specification forming part of Design No. 5,365, dated November 21, 1871.

To all whom it may concern:

Be it known that I, ISAAC BEDICHIMER, of Philadelphia, county of Philadelphia, State of Pennsylvania, have invented a Design for a Badge, of which the following is a specification:

The figure in the accompanying drawing, fully illustrates my design, which consists mainly of a shield surmounted by a spread eagle or "Totem." In the center of the shield is a representation of a tent or wigwam thrown open in front so as to show a fire burning within. Beneath the wigwam and inscribed upon a scroll or ribbon are the words "Freedom, Friendship, Charity;" and at either side of the wigwam, and

suspended from an interior shield, are weapons of war and of the chase.

I claim—

The design for a badge, substantially as described, and as represented in and by the accompanying drawing.

In testimony whereof I have signed my name to this specification in the presence of two subscribing witnesses.

ISAAC BEDICHIMER.

Witnesses:

W.M. A. STEEL,
